UNITED STATES PATENT OFFICE.

FREDERIC E. BAGER, OF WINTHROP HARBOR, ILLINOIS, ASSIGNOR TO FREDERICK C. AUSTIN, OF CHICAGO, ILLINOIS.

DRAINAGE-EXCAVATOR.

1,284,041.

Specification of Letters Patent.

Patented Nov. 5, 1918.

Application filed July 15, 1914. Serial No. 351,039.

To all whom it may concern:

Be it known that I, FREDERIC E. BAGER, a citizen of the United States of America, and resident of Winthrop Harbor, Lake 5 county, Illinois, have invented a certain new and useful Improvement in Drainage-Excavators, of which the following is a specification.

My invention relates to excavators for 0 making ditches, and more particularly those for use in making irrigation ditches and for making ditches with a dike at one or each side of the ditch.

The principal object of my invention is 5 to provide a machine having means for cutting a ditch, and provided with devices for smoothing or trimming the spoil bank as the machine moves along, whereby the excavated dirt is converted into a dike during the operation of the means for cutting the ditch, the said devices being of such character that the inner face of the dike is given a slope of the proper character, it being desirable that the same be caused to assume the angle of 10 repose of the excavated dirt, whereby the loose materials are converted into a dike of satisfactory form as the machine travels along in the direction necessary for the ditch.

It is also an object to provide certain details and features of construction and combinations tending to increase the general efficiency and serviceability of a combined ditching machine and dike builder of this 15 particular character.

To these and other useful ends my invention consists in matters hereinafter set forth and claimed.

In the accompanying drawings—

Figure 1 is a side elevation of an excavating machine having ditch cutting and dike forming means and devices embodying the principles of my invention, showing the digging apparatus in lowered position in the 15 ground.

Fig. 2 is an enlarged plan of the excavating end of said machine, with the digging apparatus in raised position.

Fig. 3 is an enlarged vertical section on line 3—3 in Fig. 1.

Fig. 4 is a vertical section through the hopper and conveyer apparatus for discharging the dirt onto the ground, said section being taken on line 4—4 in Fig. 1.

As thus illustrated, my invention comprises a body A mounted upon front wheels B and rear caterpillars C, the latter being operated or driven by the engine D in any suitable or desired manner. It will be understood that the said engine and caterpillars may be of any suitable known or approved character, and that any suitable means may be employed for controlling the forward travel of the machine.

The excavating apparatus comprises a rotary wheel E mounted on the rear end of a beam F, which latter is supported to swing up and down on the shaft G at the rear of the body of the machine. Preferably, the said shaft is supported in bearings on the frame work a of said body, and is disposed horizontally and transversely of the direction of the ditch, being located a suitable distance above the body of the machine, or above the surface of the ground. The beam F is connected with the framing a by means of an adjustable connection H, of any suitable character, whereby the wheel E may be raised and lowered by changing the angle of the beam F, in a manner that will be 65 readily understood. The adjusting connection H can be operated by hand, or it can be operated by power and through the means of suitable connection with the engine. The shaft G is provided with sprocket wheels g upon which are supported the sprocket belts g¹, said belts extending around the wheel E, the latter being operated with sprocket teeth of any suitable character for this purpose.

The excavating buckets g², of any suitable form or character, are mounted on said sprocket belts, and are thereby adapted to travel in the direction indicated by the arrow in Fig. 1, whereby each bucket takes up a load at the bottom of the ditch and then travels upward to the point of discharge above. With the construction shown, the said point of discharge is approximately 70 above and a little to the right of the shaft G, as shown in Fig. 1, and any suitable means 75 can be employed for causing the buckets to successively discharge their loads as they turn upside down at this point and pass around the said shaft. The wheel E is provided with side cutters e for forming the 80 sides of the ditch, these cutters being preferably bars which are suitably fastened to the wheel, and which are radially disposed

relative to the axis of said wheel. It will also be seen, however, that these cutters, as shown in Fig. 3, are farther apart at their upper ends, when in the ditch, than at their lower ends; and that for this reason the sides of the ditch incline outwardly to some extent and are of a sloping character. The dirt shaved off by these cutters is taken up by said buckets and dumped at the points above mentioned. The device for converting the excavated dirt into a dike at one side of the ditch, or at both sides thereof, comprises the cutters e^1 which are suitably fastened to the sides of the wheel E, and which are so arranged that in effect they form outwardly tapered hubs for the wheel, which hubs are secured in any suitable manner to the shaft or journal e^2 that rotates in suitable bearings e^3 , or which is supported in any other suitable manner on the lower end of the tilting beam. As shown in Fig. 3, it will be seen that the cutters e^1 are disposed at an angle to the cutters e , so that any cutter e and the adjacent cutter e^1 form an obtuse angle between them, the apex of said angle being slightly rounded at e^4 in the manner shown, it being observed that these rounded portions of the cutters are immediately above the surface of the ground. Coöoperating with these cutters e^1 in forming the dikes X at each side of the ditch are the rearwardly extending conveyers I which are suitably supported on the rear end of the body A and which are arranged with their forward ends in position to receive the dirt from the spouts J, said spouts being at the lower end of a hopper K which receives the dirt directly from the buckets. These conveyers I are of any suitable character, and are operated through the means of any suitable power transmitting connection with the engine D on the machine body. It will also be seen that the rear ends of these conveyers I are directly in front of and in line with the cutters e^1 , whereby the latter are compelled to plow through the spoil or ridges of loose dirt discharged upon the ground by said conveyers. As the excavator travels slightly forward, these cutters e^1 trim or shave the inner sides of the spoil banks in such manner as to convert the latter into dikes of the proper character, the inner face or inclined surface of each dike having the angle of repose of the loose materials or excavated dirt. It will also be seen that the said conveyers I coöperate with the said cutters e^1 to prevent the formation of a berm between the dike and the side of the ditch, inasmuch as the loose dirt does not leave any exposed ground surface between the dike and the upper edge of the side of the ditch. Thus the two dikes are formed with gently sloping inner sides or faces, and these inner sides are curved where they join the sides of the ditch, thus preventing an

abrupt angle at this point, and insuring the formation of a ditch having dikes which will remain firmly and solidly in place without danger of the loose dirt sliding into the ditch after the machine has traveled 70 forward—that is to say, the possibility of the loose dirt sliding into the ditch is greatly reduced by smoothing or flattening of the inner sides of the dikes, and by the manner in which the loose dirt is left along the 75 edges of the ditch.

The devices e^1 , it will be seen, only operate above ground on the loose dirt of the spoil banks, and do not cut the trench in the ground. But both the trench-cutting means 80 and said devices operate about the same horizontal axis (shaft e^2), which latter is transverse of the ditch.

What I claim as my invention is:

1. An excavator comprising means for 85 cutting a ditch, apparatus for discharging the excavated dirt at the side of the ditch, to form a spoil bank, mechanism for slowly moving the machine forward during the operation of said means, and devices for 90 properly sloping the face of said bank to form a dike as the machine moves along, said means including a wheel having cutters for forming a ditch with sloping sides, and said devices including cutters disposed in 95 such position that the face of the dike forms an obtuse angle with the adjacent side of the ditch.

2. An excavator comprising means for 100 cutting a ditch, apparatus for discharging the excavated dirt at the side of the ditch, to form a spoil bank, mechanism for slowly moving the machine forward during the operation of said means, and devices for 105 properly sloping the face of said bank to form a dike as the machine moves along, said means including a wheel, link belts traveling on said wheel, instrumentalities for operating said belts to rotate said wheel, buckets on said link belts, and said devices 110 consisting of cutters forming the hub of said wheel.

3. An excavator comprising means for 115 cutting a ditch, apparatus for discharging the excavated dirt at the side of the ditch, to form a spoil bank, mechanism for slowly moving the machine forward during the operation of said means, and devices for 120 properly sloping the face of said bank to form a dike as the machine moves along, said means including a wheel having cutters for sloping the sides of the ditch, a tilting beam for supporting said wheel in the ditch, an endless series of buckets on said wheel, and said devices including bars on said 125 wheel, each said bar being disposed in position to engage the spoil bank at the angle of repose of the loose excavated dirt.

4. An excavator comprising means for 130 cutting a ditch, apparatus for discharging

the excavated dirt at the side of the ditch, to form a spoil bank, mechanism for slowly moving the machine forward during the operation of said means, and devices for properly sloping the face of said bank to form a dike as the machine moves along, said apparatus including a conveyer for dumping the dirt ahead of said means, and a hopper for delivering the excavated dirt to said conveyer, the said devices and conveyer co-operating to prevent the formation of a berm between the dike and the ditch, the rear end of said conveyer being disposed directly in line with said devices.

5 5. An excavator comprising means for cutting a ditch, apparatus for discharging the excavated dirt at the side of the ditch, to form a spoil bank, mechanism for slowly moving the machine forward during the operation of said means, and devices for properly sloping the face of said bank to form a dike as the machine moves along, said means and devices including a wheel having cutters disposed at an angle suitable for the sides of the ditch, and having other cutters disposed at a different angle for the dike, the last mentioned cutters in effect forming outwardly tapered hubs for said wheel.

10 6. An excavator comprising a wheel, a series of buckets carried by said wheel to cut a trench, apparatus to discharge the excavated dirt in front of said wheel, and means associated with and operated by said wheel to

form the discharged or loose excavated dirt into a dike at the side of the trench.

35

7. The structure of claim 6, in which said wheel is provided with cutters to shape the side of the trench below said dikes.

8. The structure of claim 6, in which said means include cutters forming an outwardly tapered hub for said wheel.

40

9. The structure of claim 6, in which said wheel is disposed at the rear end of the machine, and in which a link belt is provided to support said buckets and drive said wheel.

45

10. In an excavator, the combination of a body equipped to travel along the surface of the ground, a tilting digging beam at the rear of said body, supported thereon, a wheel on said beam, means carried by said wheel to cut a trench, means to discharge the excavated dirt onto the ground at each side of the trench, mechanism to raise and lower said beam, power transmitting connections to operate said wheel, cutters on the sides of said wheel to shape the sides of the trench, and cutters on the hubs of said wheel to form the excavated dirt into sloping banks above the sides of the trench.

Signed by me at Chicago, Illinois, this 29th day of June, 1914.

FREDERIC E. BAGER.
